UNITED STATES PATENT OFFICE.

CONRAD M. CONRADSON, OF MADISON, WISCONSIN.

TURRET TOOL-POST.

1,143,252.

Specification of Letters Patent. Patented June 15, 1915.

Application filed April 25, 1914. Serial No. 834,476.

To all whom it may concern:

Be it known that I, CONRAD M. CONRADSON, citizen of the United States, resident of Madison, county of Dane, State of Wisconsin, have invented certain new and useful Improvements in Turret Tool-Posts, of which the following is a specification.

The object of my invention is to provide a lathe tool post of comparatively simple construction and one which can be easily and quickly adjusted to its working position.

A further object is to provide a tool post which will greatly facilitate the operation of the lathe and therefore increase its capacity, and a still further object is to provide a post for use on that class of work which cannot be economically handled on an engine lathe or advantageously on a turret lathe.

20 The invention consists generally in various constructions and combinations, all as hereinafter described and particularly pointed out in the claims.

In the accompanying drawings forming 25 part of this specification, Figure 1 is a vertical sectional view through a turret tool-post embodying my invention, Fig. 2 is a plan sectional view of the same, on the line $x-x$ of Fig. 1, Fig. 3 is a vertical sectional 30 view, taken on a line at right angles substantially to the section line of Fig. 1, Fig. 4 is a sectional view on the line $y-y$ of Fig. 3.

In the drawing, 2 represents the longitudinal slide of the lathe and 3 the cross slide.

4 is a standard mounted on the cross slide and projecting upwardly therefrom. The upper portion of this standard is circular in form and preferably has an exteriorly threaded surface as at 5, and an interiorly threaded split collar 6 preferably encircles said standard and engages the threads thereon, and is provided with an operating handle 7 by means of which said collar may be 45 rotated to raise or lower it on said standard. Said collar is provided at its upper end with an inwardly projecting annular flange 8 that preferably fits within an annular groove 9 formed in the lower portion of a 50 turret tool-post 10 and is provided with a flat under surface having a series of notches 11 formed thereon which are adapted to receive teeth 12 provided in the top of the standard 4, thereby locking the post on said standard against premature rotary movement and facilitating the indexing of the post in the operation of the machine. The post also has preferably a centrally arranged socket 13 therein adapted to receive a stud 14 concentric with said standard and projecting upwardly therefrom, and the walls of said socket have recesses 14' therein adapted to receive the finder ball 15 that is preferably mounted in the stud 14 and yieldingly projected against 60 the walls of the socket by a compression spring 16. The walls of the socket are rounded to fit the surface of the ball, and to enable the operator to easily turn the post on the standard, the entrance of the ball 65 into the socket indicating each quarter revolution of the post and enables the operator of the lathe to accurately and quickly adjust the post. The post is provided with horizontal recesses 17 to receive the tools, which 70 are clamped therein by suitable means, such as the bolts 18. A horizontal tool holder 19 is preferably mounted in the post 10 and capable of longitudinal and rotary movement therein, said holder being preferably 75 provided with a series of notches 20, preferably four in number, which are adapted to receive teeth 21 provided on the lower end of a slide 22 that is preferably mounted in the top of said post and is held against 80 rotary movement by suitable means, such as the spline or guide 23. The slide 22 has preferably a threaded connection with the lower end of a stud 24 that is mounted in a cap 25 and provided with an operating handle 26. When this stud is revolved, the slide 85 will be raised or lowered to withdraw its teeth from a notch in the tool post beneath or project them into said notch. A plunger 27 is mounted to slide in the lower portion 90 of the slide 22 and is held in a projected position, preferably by means of a spring 28, said plunger having a limited movement between the teeth 21 and provided with a rounded lower end which, while entering the 100 notch 20 and preventing premature rotary movement of the tool holder, will allow the

operator to grasp the tool holder and revolve it, the plunger dropping into a socket with each quarter revolution and indicating to the operator the exact position of the tool holder, and the fact that a notch is directly beneath the teeth of the slide. When the stud 24 is tightened, the tool holder will be locked against both longitudinal and rotary movement.

10 In using the post, the collar 6 is revolved until the opposing surfaces of the post and standard are separated by the raising of the post, when it can be rotated in the collar post, until the tool holders and tools are adjusted 15 in the desired position with respect to the work. At such time, the horizontal tool holder may, of course, be withdrawn or retracted out of the way. When this horizontal holder is used, the toothed slide is 20 loosened and the holder may then be moved lengthwise and rotated as desired to set it in the proper position. The withdrawal of the tooth on the slide from the recess in the holder will still allow the spring-pressed device to enter the recess and aid the operator 25 in determining the proper rotation of the holder to register the recess with the tooth on the slide. When the horizontal holder has been properly adjusted, the handle 26 30 may be operated and the slide locked in engagement with the holder.

In various ways the details of construction herein shown and described may be modified and still be within the scope of my 35 invention.

I claim as my invention:

1. A turret tool post comprising two members, one adapted to index in a plane parallel to the axis of the work, the other 40 member having its axis at right angles substantially to the axis of the first named member and carried thereby.

2. A turret tool post comprising a revolving tool carrier and a tool holder mounted for 45 rotation in a direction at right angles to the plane of rotation of the carrier and an indexing means for said tool holder.

3. A tool post comprising a polygonal turret having a plurality of tool holders, 50 and a tool holder mounted in said turret and an indexing means for said tool holder.

4. The combination, with a standard having a plurality of teeth formed in its upper surface, and a centrally arranged stud projecting above said surface, of a tool post 55 having a centrally arranged socket to receive said stud and recesses in its under surface to receive said teeth, the engagement of said teeth with said recesses locking said post against rotary movement, an indexing means for said post, a finder device co-operating with said stud and the wall of said socket, means for raising and lowering said post to disengage or engage said teeth with

said recesses, and a plurality of tool holders 65 mounted in said post.

5. A turret tool post comprising a member having a plurality of tool holders and mounted for rotation on a vertical axis, and a second member carried by said first named 70 member and slidable therein transversely with respect to the axis of said first named member, said second named member having a plurality of tool holders and an indexing means for said second member. 75

6. A lathe tool post comprising a rotating member having a horizontal socket therein, a tool holder fitting within said socket and having longitudinal recesses at intervals therein, a toothed slide for entering said recesses and locking said tool holder against rotary movement, and a spring pressed device for entering said recesses and preventing premature rotary movement of said holder while indicating to the operator the 80 proper registration of said toothed slide with a recess.

7. A lathe tool post comprising a rotating member having a horizontal socket therein, a tool post seated within said socket and 90 having a plurality of recesses, a toothed member for entering said recesses and locking said holder, means for projecting or retracting said toothed member, and a yielding device adapted to enter said recesses and yieldingly 95 resist rotary movement of said holder while indicating proper registration of a recess with said toothed member.

8. A turret tool post comprising a member mounted for rotation in a horizontal 100 plane and provided with a plurality of tool holders, a second member carried by said first named member to revolve therewith and also capable of rotation on its own axis and having an endwise movement in said 105 first named member.

9. A turret tool post comprising a member mounted to revolve on a vertical axis and provided with a plurality of tool 110 holders, and a tool holder mounted for endwise movement in said first named member, and indexing devices for said member and said holder.

10. A turret tool post comprising a member mounted for rotation on a vertical axis 115 and provided with a plurality of tool holders, and a second member mounted in said first named member above and transversely of the axis thereof and having a rotary and longitudinal movement in said 120 first named member and provided with a plurality of tool holders.

11. A turret tool post comprising a member mounted for rotation on a vertical axis and provided with a plurality of tool holders 125 and having an indexing means, and a second member mounted horizontally in said first named member and capable of rotation

therein and having tool holders and an indexing and locking means for said second member.

12. A turret tool post comprising a member threaded for rotation on a vertical axis, a boring bar horizontally mounted in said member for rotation and longitudinal movement therein, an indexing device for said boring bar adapted to hold it against pre-

mature rotary movement, and means for positively locking said boring bar against rotary movement.

In witness whereof, I have hereunto set my hand this 20th day of April 1914.

CONRAD M. CONRADSON.
